US00D870148S

(12) **United States Design Patent** (10) Patent No.: **US D870,148 S**
Chuang et al. (45) Date of Patent: **** Dec. 17, 2019**

(54) **DISPLAY SCREEN WITH GRAPHICAL USER INTERFACE**

(71) Applicant: **AVISION INC.**, Hsinchu (TW)

(72) Inventors: **Kai-Chieh Chuang**, Hsinchu (TW);
Ting-Kuo Chu, Zhubei (TW);
Hsin-Chen Lee, Hsinchu (TW);
Yu-Ling Chen, Hsinchu (TW);
Yung-Ting Hsu, Hsinchu County (TW)

(73) Assignee: **AVISION INC.**, Hsinchu (TW)

(**) Term: **15 Years**

(21) Appl. No.: **29/638,912**

(22) Filed: **Mar. 1, 2018**

Related U.S. Application Data

(63) Continuation-in-part of application No. 29/605,102, filed on May 23, 2017, now abandoned, which is a continuation-in-part of application No. 29/552,011, filed on Jan. 19, 2016, now abandoned.

(57) **CLAIM**

The ornamental design for “display screen with graphical user interface,” as shown and described.

DESCRIPTION

FIG. 1 is a front view of a display screen with graphical user interface;

FIG. 2 is a front view thereof, with alternate broken line elements;

FIG. 3 is a front view thereof, with alternate broken line elements;

FIG. 4 is a front view thereof, with alternate broken line elements; and,

FIG. 5 is a front view thereof, with alternate broken line elements.

The dot-dash broken line represents the display screen and forms no part of the claimed design.

The remaining broken lines represent elements of the graphical user interface and form no part of the claimed design.

1 Claim, 5 Drawing Sheets
